PLUNGER CONTROL DEVICE

Harold W. Fletcher, Houston, Tex., assignor to
 Hughes Tool Company, Houston, Tex., a corporation of Texas

Application July 25, 1932. Serial No. 624,429

8 Claims. (Cl. 103—52)

My invention relates to plunger lift devices for use in raising liquid from wells by pneumatically operated means. It pertains particularly to the control of the plunger at the upper end of its stroke by regulating the flow of the pressure fluid from the well.

In the operation of plunger lift devices the load of liquid above the plunger is discharged at the end of the upward stroke and then the plunger 10 passes the outlet, allowing the gaseous pressure fluid to exhaust from said outlet. The valve in the plunger opens and the plunger starts to drop almost immediately. In doing so, it falls into the rising stream of the exhausting gaseous fluid 15 and may be blown back and the valve again closed, thus interfering with the desired operation of the device.

It is an object of my invention to prevent the immediate falling of the plunger until the gaseous 20 fluid has, to a large extent, exhausted, thus allowing the free and expeditious dropping of the plunger on the downward stroke when it is released.

I desire to provide a flow connection between 25 the extreme upper end of the eduction tube and the flow pipe carrying the liquid from the well and, by means in said flow pipe, to exert a suction on said upper end of the flow line sufficient to retain the plunger at the upper end of the eduction 30 tube until the gas or air has exhausted from the eduction tube sufficiently so as not to interfere with the fall of the plunger.

I contemplate employing the flow of the exhausting gas to act above the plunger and by reducing the fluid pressure on the upper side of 35 the plunger, prevent its immediate dropping after its upward stroke has been completed.

In the drawing herewith Fig. 1 is a side view, partly in elevation and partly in central vertical 40 section, of the equipment of a plunger lift apparatus with my improvement employed thereon.

Fig. 2 is a vertical section of the lower end of the well with the plunger lift apparatus therein.

The apparatus includes an outer well casing 1 which extends downwardly a sufficient depth to hold up the walls of the well. At the upper end 45 of the casing is the special casing head 2 having at its lower end a lateral opening in which is connected the pipe 3 controlled by the valve 4. Above the pipe 3 there is an inner annular flange 5 which serves as a support for the eduction tube.

Above this flange 5 is a lateral outlet port 6 in which is screwed the flow pipe 7. The upper end 55 of the casing head is formed with a bonnet 8 which closes the casing head except for the open-

ing 9 in which is connected the upper extension 10 of the eduction tube. This extension is closed by a cap 11 having therein a tubular shock absorbing member 12 of rubber or similar material. The upper end of the cap has an axial opening in 60 which is connected the bypass pipe 13 leading, by way of the choke device 15, and the pipe 16 to the T 17 which forms the housing for an ejector device in the flow line 7.

The ejector device is of common construction, 65 the section of pipe 18 in the flow line has an inward upset and a restricted passage 19 leading to the interior of the chamber 22 in the housing 17. The section of flow line 20 which is connected into the downstream end of the housing 70 17 is also upset inwardly and formed with a Venturi passage 21, the flaring end of which receives the tapered end of the section 17. The rapid flow of fluid through the chamber 22 exerts a suction in pipe 16 due to the reduction of pressure about the ejector device. 75

The eduction tube 14 has, within the casing head, a supporting head 23 having a radial flange 24 resting upon the flange 5 in the casing head and serving to form a seal about the tube within 80 the casing head. The tube 14 within the casing is perforated at 25 to allow outlet for the fluid from the eduction tube to the interior of the casing head. The lower end of the eduction tube has a cross-shaped stop member 26 below which 85 is the strainer plug 27 through which fluid enters the tube. This construction of the eduction tube is not a part of the present invention.

The plunger operating in the eduction tube is shown at the upper extension of the tube where 90 it will be at the upper end of its stroke. This plunger includes a tubular body 28, the interior bore of which tapers downwardly. At the lower end of this body is a head 29 having a valve support and guide 30 at its lower end and a valve seat 95 toward its upper end. The valve stem 31 passes through the guide and projects below to contact with the stop 26 at the lower end of its stroke and thus move the valve to closed position.

In the flow line 7 may be placed a gate valve 100 32 to manually close off the flow line when desired.

In operating, the plunger at the lower end of its stroke will be lifted with its load of liquid by the pressure of gaseous fluid accumulating below the plunger. The load of liquid will be discharged through the perforations 25 to the flow line 7. The plunger will be moved past the outlet openings and, as the line 16 forming the bypass is open, the gas and liquid above the plunger will leak through the bypass as fast as the choke 110

15 will allow it. The choke will be adjusted to prevent the plunger hitting the bumper 12 with any great force.

As the plunger passes the outlet openings, the 5 gas behind the plunger will rush through the outlet ports to the flow line. The flow of fluid through the ejector member 17 will lower the pressure above the plunger and the comparatively great pressure below the plunger will hold 10 it in place, as shown in Fig. 1, until the gas has sufficiently exhausted to nearly balance the pressure above and below the plunger and thus allow the plunger to drop.

The valve in the plunger may then drop open, 15 or may remain closed until the gas current is encountered at the openings, and the plunger will then be agitated in the outgoing gas and the valve thus caused to drop open and permit the plunger to fall freely to the lower end of 20 the tube.

When the gas pressure in the eduction tube is lowered following the discharge of the load, the liquid will rise in the eduction tube and the plunger will thus strike the liquid before it hits 25 its seat 26 and there will be no jar upon the apparatus as the plunger sinks through the liquid to the seat, where the valve is closed again.

The advantages of this device arise through the operation of the suction means above the 30 plunger which prevents its fall until the larger part of the gas has exhausted. By doing this, the dropping of the plunger is not interfered with. The gas still continues to flow, but not with sufficient force to impede the fall of the plunger as soon as the valve opens and this opening of the valve occurs as soon as the flow of gas acting 35 on the plunger and valve agitates the plunger in the tube. I am thus enabled to prevent the fall of the plunger prematurely, before the violence of the gas discharge has dissipated. The operation of the device is hence made more uniform and accurate and the difficulties previously experienced through the immediate fall of the plunger are avoided.

40 15. What I claim as new is:

1. A plunger lift apparatus; including an eduction tube, a lateral flow line connected therewith and a plunger movable by pneumatic pressure from the lower end to the upper end of said tube in combination with a by-pass from the upper end of said tube above said flow line to said flow line and means to reduce the normal fluid pressure in said by-pass to hold said plunger at the downstream end of said bypass.

45 2. A plunger lift apparatus; including an eduction tube, a lateral flow line connected therewith and a plunger movable by pneumatic pressure from the lower end to the upper end of said tube in combination with a by-pass from the upper 50 end of said tube above said flow line to said flow

line and means in said flow line to reduce the normal fluid pressure in said by-pass to hold said plunger at the downstream end of said by-pass.

3. In a plunger lift device a well casing, an 80 eduction tube therein, a plunger in said tube, a flow line from said casing, outlets from said tube to said casing, an eduction tube extension above said casing, and means in said flow line connected to exert a suction at the upper end 85 of said extension to act upon said plunger and tend to hold it at the upper end of said tube extension while pressure fluid is flowing in said line.

4. In a plunger lift device a well casing, an 90 eduction tube therein, a plunger in said tube, a flow line from said casing, outlets from said tube to said casing, an eduction tube extension above said casing, an ejector in said flow line connected with the upper end of said extension 95 to lower the fluid pressure above the plunger for the purpose described.

5. In a plunger lift device including a casing, a casing head thereon, an eduction tube in said casing discharging into said head and fitting upwardly through said casing head, a plunger in said tube and a flow line from said casing head; in combination with means in said flow line responsive to the discharge of fluid through said 100 flow line to reduce the pressure at the upper end 105 of said eduction tube for the purpose described.

6. In a plunger lift device including a casing, a casing head thereon, an eduction tube in said casing discharging into said head and fitting upwardly through said casing head, a plunger in 110 said tube and a flow line from said casing head; in combination with a bypass connecting the upper end of said eduction tube with said flow line at a point spaced from said casing head, and means in said flow line responsive to the flow of 115 fluid in said flow line to reduce the fluid pressure in said bypass.

7. In a plunger lift device including an eduction tube, an outlet therefrom below its upper end, a flow line connected with said outlet, a 120 plunger in said eduction tube adapted to move past said outlet to the upper end of said tube, and means responsive to the flow of fluid in said flow line to retain said plunger above said outlet.

8. In a plunger lift device including an eduction tube, an outlet therefrom below its upper end, a flow line connected with said outlet, a plunger in said eduction tube adapted to move past said outlet to the upper end of said tube, the improvement comprising creating a preponderance of fluid pressure below said plunger to retain said plunger above said outlet until the flow of fluid in said flow line at each stroke has materially decreased.

HAROLD W. FLETCHER. 125
